UNITED STATES PATENT OFFICE.

FRANÇOIS BAVEREY, OF OULLINS, FRANCE, ASSIGNOR TO SOCIETE DU CARBURATEUR ZENITH, OF LYON, FRANCE, A CORPORATION OF FRANCE.

CARBURETER.

1,251,623.

Specification of Letters Patent.

Patented Jan. 1, 1918.

Application filed February 7, 1914. Serial No. 317,277.

To all whom it may concern:

Be it known that I, FRANÇOIS BAVEREY, a citizen of the French Republic, residing at Oullins, in France, have invented certain new and useful Improvements in Carbureters for Explosion-Motors, of which the following is a specification.

This invention relates to improvements in carbureters for explosion motors.

10 The invention provides means for opening in correlation a passage for fresh air and the nozzles of one or more carbureters having their orifices in this air passage and supplying an emulsion rich in fuel and automatically proportioned.

15 The devices adopted are arranged in such a manner that the orifices of the nozzles which feed the emulsion are located in the most throttled portion of the air passage so as to obtain the best atomization.

20 Each carbureter supplying the emulsion rich in fuel comprises a nozzle or a series of nozzles which in accordance with the suction, automatically supply the quantity of fuel necessary for insuring a good mixture. For example, each carbureter comprises an ordinary nozzle and a constant supply nozzle, that is to say, a nozzle delivering at the bottom of a well open to the atmosphere.

25 It is also possible to proportionate the supply of emulsion to the supply of air for all positions of the member for throttling the gases by giving the air passage and the orifices for the passage of the emulsion cross-sections of appropriate form.

30 A carbureter thus arranged will therefore supply suitable mixture for all apertures of the carbureter and all speeds of the engine.

35 The annexed drawings illustrate the invention.

Figures 1 and 2 illustrate two forms of construction of the apparatus which are shown diagrammatically.

40 Fig. 3 is a vertical section of a practical embodiment of the diagrammatic arrangement shown in Fig. 1.

Fig. 4 is a plan view of Fig. 3.

45 Fig. 5 is a section on line A—A of Fig. 3. Fig. 6 is a detail sectional view showing certain of the parts.

In Fig. 1 of the drawings the reference character *a* designates an emulsion tube which extends into a rectangular member *b* through which the air passes to the engine. 55 The outlet of tube *a* is in the form of a narrow slot *e*, whose length is equal to one of the dimensions of the cross-section of the passage through the member *b*. Slidably mounted over this slot *e* and extending 60 across the other cross-sectional dimension of the passage for the air is a throttle valve *d* which is arranged to be moved back and forth to increase or decrease the supply of air, and simultaneously increase and 65 decrease the size of the opening *e* through which the emulsion passes.

In Fig. 2 I have shown a similar device with a plurality of emulsion tubes *a*¹, *a*² and *a*³, which are provided with narrow outlets *e*¹, *e*² and *e*³, respectively, which open into the air passage leading to the engine. Emulsion may be fed to these various tubes in any desired manner, but the arrangement is such that the area of the emulsion inlet 75 will be simultaneously increased or decreased as the area of the air inlet is increased or decreased.

In Figs. 3 to 5 I have shown one form of device, and in which *p*² designates a casing 80 having an air passage *b* therethrough which communicates with the intake of the engine. Extending into this casing from one end is an emulsion or a rich mixture tube *t* having a plurality of slots *f* through the wall thereof, and which slots extend approximately across the full width of the opening *b*. This tube *t* is inserted through a cylindrical opening in one side wall of the casing *p*². This tube *t* is preferably made in two parts, 90 the outer portion being in the form of a Venturi or choke tube, and is inserted through the same opening through which the other portion of the tube *t* is inserted. The end of this opening is inclosed by means 95 of a hollow cap *g* having openings through the side wall thereof which are provided with a screen *g*¹, and through which air is admitted to the Venturi tube and the tube *t*. *j* is a jet of ordinary type and is fed from 100 the constant level chamber in the ordinary manner, the tip *i* of said jet is calibrated to

accurately measure the fuel. This jet is inserted in passage *l* which opens into tube *t*, this passage *l* receiving gasoline from well *o*, open to the atmosphere in the well known 5 manner. The well *o* is fed through the opening *h* and communicates with passage *l* by means of chamber *k*.

Slidably mounted across the air passage *b* in the casing *p*² is a throttle valve *p* which 10 is in the form of a piston, and which telescopically engages the tube *t*, the arrangement being such that when the valve *p* is moved in one direction it will reduce the size of the air opening through the casing 15 and simultaneously reduce the size of the openings *f* leading from the emulsion tube *t*, and when moved in the opposite direction it will simultaneously increase the area of the air inlet and the openings from the 20 emulsion tube. This throttle valve *p* is provided with a valve stem *p*¹ which extends through a head connected to the casing *p*².

In order to feed a mixture to the air channel for slow speed running, I have provided 25 an auxiliary jet *r* which communicates with the air chamber opposite the end of the throttle valve, and which is fed with fuel from the well *o* through the passage *s*¹.

The advantages of my invention result 30 from the provision of means for feeding an emulsion to the air intake of an explosive engine, together with means for automatically varying the size of the air inlet and the size of the emulsion inlet thereto, so as 35 to insure a good mixture for all positions of the throttle valve and all speeds of the engine.

What I claim as my invention and desire 40 to secure by Letters Patent of the United States is:—

1. In a carbureter, the combination of an air intake arranged to supply a fuel mixture to the engine, a jet having an emulsion passage leading therefrom into the air intake, 45 said jet opening below the level of the liquid in the constant level reservoir into a well communicating with the atmosphere, and a throttle arranged to simultaneously vary the area of the air intake and the area of the 50 opening from the emulsion passage into said intake.

2. In a carbureter, the combination of an air intake arranged to supply a fuel mixture to the engine, a jet having an emulsion 55 passage leading therefrom into the air intake, said jet opening below the level of the liquid in the constant level reservoir into a well communicating with the atmosphere, and a single throttle member arranged to 60 simultaneously vary the area of the air intake and the area of the opening from the emulsion passage into said intake.

3. In a carbureter, the combination of a

constant level reservoir, an air intake arranged to supply a fuel mixture to the 65 engine, a fuel jet having an emulsion passage leading therefrom into the air intake, said passage having a venturi into which said jet opens, a well communicating with the atmosphere and with the constant level 70 reservoir, said jet communicating with said well at a point below the level of the liquid in the constant level reservoir, and a throttle arranged to simultaneously vary the air intake and the area of the opening from the 75 emulsion passage to the said intake, substantially as described.

4. In a carbureter, an air conduit, a fuel conduit discharging thereinto, said fuel conduit being provided with two sources of 80 fuel supply, one providing a supply variable per unit of time, and one constant per unit of time, and a throttle arranged to simultaneously vary the area of the air conduit and the area of the opening from 85 the fuel conduit thereinto.

5. In a carbureter, an air conduit, a fuel conduit subject to the influence of air passing through the air conduit, the fuel conduit being provided with a suction-controlled fuel feed, and another fuel feed giving a fuel supply increasing at a less rate than the air supply, and a throttle arranged to simultaneously vary the area of the air conduit and the area of the opening 95 from the fuel conduit thereinto.

6. In a carbureter, the combination of an air intake arranged to supply a fuel mixture to the engine, an emulsion passage leading into the air intake, an air inlet 100 for the emulsion passage, a suction-controlled fuel feed supply, and a fuel feed giving a fuel supply increasing at a less rate than the air supply, both said fuel feeds entering the emulsion passage, and a 105 throttle arranged to simultaneously vary the area of the air intake and the area of the opening from the emulsion passage.

7. A carbureter, comprising a casing, an air intake extending through said casing, an emulsion tube extending into said air intake and having an elongated opening therethrough, means for feeding both air and oil to said tube, a reciprocating throttle valve mounted within said casing and arranged to slide across the air intake opening and the opening from the emulsion tube, to simultaneously increase or decrease the feed of air and emulsion.

8. A carbureter, comprising a casing 120 having an air passage therethrough, an emulsion tube extending through the wall of said casing into the air passage, means for feeding air to said emulsion tube, means for feeding oil to said emulsion tube, said 125 emulsion tube having an elongated slot

through its walls, a piston valve mounted within the casing and surrounding the emulsion tube, said piston valve being arranged to simultaneously close the slot 5 from the emulsion tube and the air passage, and a piston rod connected to said piston.

In witness whereof I have signed this specification in the presence of two witnesses.

FRANCOIS BAVEREY.
